DEVICE FOR DIFFERENTIAL MOTION

William Kimmich, Flushing, N. Y., assignor to
 Radio Corporation of America, a corporation of
 Delaware

Application June 1, 1946, Serial No. 673,869

4 Claims. (Cl. 178—53)

1

This invention relates to a new and useful device for differential motion whereby two objects can be displaced angularly in opposite directions, and is particularly adapted to provide differential motion to shift the distributor brushes of multiplex telegraph printers in equal but in opposite directions in order to place a local and received signal in the proper phase relation with respect to each other.

An object of this invention is to provide a simplified and improved device which will give differential motion for any mechanical or electrical equipment.

Briefly, this invention is an improved housing arrangement comprising two spaced end plates. Retained within the housing and supported by four brackets are two moving gear assemblies, the outer gear assembly comprising two sectors of internal gears secured to a cylindrical sector and the inner gear assembly comprising two external or spur sector gears which are also secured to another cylindrical sector. The sector gears are arranged so that they mesh with a small pinion having a shaft to rotate simultaneously each sector gear in an opposite direction. A brush holder is insulatingly secured to each of the two sector gears.

Prior to the conception of this invention, insofar as I know, there were no means to accomplish the displacement of the distributor brushes with respect to the commutator segments of the multiplex printer equipment. With this invention, it is possible to impart motion to the internal gear and external gear assemblies so that each brush is displaced an equal distance but in an opposing direction, which greatly facilitates the operation of telegraph multiplex printers.

One specific use of the device of this invention is for a frequency correction unit for a seven unit code combination. In the operation of such a frequency correction unit, the frequency of the apparatus is operated at 42 $\frac{1}{2}$ cycles per second, which frequency permits the positive half of the printer equipment to be divided into seven equal units, and the negative half of the printer equipment to also be divided into seven equal units, making a total of fourteen combinations. This code combination, when multiplied by the 42 $\frac{1}{2}$ cycles, equals a total of 600 code impulses per second. It will be seen that with such a frequency and the large number of impulses, it will be absolutely necessary to have both the local and received signal in proper phase relation with respect to each other. Therefore, by connecting the brushes of the device of this invention with a suitable electronic frequency correction unit (which corrects the frequency of the local receiver by changing the bias on an electronic tube) it will be possible to bring both frequencies in exact alignment.

This invention will best be understood by referring to the accompanying drawing, in which:

2

Fig. 1 is a plan view taken through the center between the two end plates;

Fig. 2 is a cross-section of Fig. 1, the section being taken on lines 2—2;

Fig. 3 is a diagram of the device of this invention applied to a frequency correction unit; and

Fig. 4 is a cross-section of Fig. 1, the section being taken on lines 4—4.

Referring now in detail to Figs. 1 and 2 of the drawing, a housing is shown having two end plates 1 and 1A, of insulation material, which are spaced parallelly by means of four metallic spacers 2 located in each corner of end plates 1 and 1A, the spacers being secured by means of machine screws 2A. Retained within the two end plates and supported by four brackets 8 are two gear assemblies. The outer gear assembly comprises two sectors of internal gears 3 and 3A which are secured to a cylindrical sector 5 and fastened by means of machine screws 5A. The inner gear assembly comprises two spur sector gears 4 and 4A which are secured to a cylindrical sector 6 by means of machine screws 4B. The internal and external sector gears are chosen and arranged to slide on brackets 8 so that they will mesh with a small pinion gear 7 which is provided with shaft 7A, bearings 7B, 7C, and an operating knob 7D, the knob being secured by means of a set screw 7E. The brackets 8 are secured to panels 1 and 1A by means of machine screws 8A and positioned so that the gears 3, 3A, 4 and 4A will move in equal but opposing directions. In order that the gears will not become detached from the brackets 8, stop pins 9 are provided at each end of the gears. In order to approach a uniform displacement, it is essential to choose as small a pinion gear and sector gears as possible. In order that the mechanical device of the invention may be used to shift the distributor brushes of multiplex telegraph printers, the cylindrical sectors 5 and 6 are each provided with a brush holder which comprises a tubular housing member 10 having located therein a copper gauze brush 11, a brush cap 12, a brush tension spring 13, and an adjustable threaded stud 14. The tubular brush housing member 10 is provided with an insulating tube 15 which is secured to the central portion of each cylindrical sector. In order that the brush housing may be free to move when the pinion gear 7 is rotated, open slots 16 and 17 are provided in the cylindrical sectors. The insulating tube is secured to the cylindrical sectors by means of a set screw 18. A flexible connection lead 19 is fastened to the upper portion of stud 14 and is retained in position by means of suitable washers and nuts 20 and 21. In order that the tension on brush 11 may be adjusted, the upper portion of stud 14 is provided with a screw driver slot 22. The insulating end plates 1 and 1A are each provided with central apertures 23 and 24 through which pass a rotary

shaft 25 which is arranged to rotate simultaneously with the multiplex printer equipment. An insulating disc 26 is secured to shaft 25 by means of a set screw 27. The outer periphery of the insulating disc 26 has located thereon two semi-circular collector rings 28 and 29 which are secured to the disc by means of small flat head screws 30; or, if desired, the rings 28 and 29 may be molded directly into position by making disc 26 of molded insulating material.

In the operation of this device, as the shaft of pinion 7 is rotated in its bearings by the operation of knob 7D, it imparts motion to the internal and spur gear brush holder assembly. The direction of displacement of each brush holder, however, is opposite, and the travel equal, as will be noted when points A and B are observed with respect to the pinion axis or a center reference point C. The distributor brushes 11 are electrically connected to any suitable means, such as a frequency correction unit shown in Fig. 3, which places the local and received signals in proper phase relation with respect to each other before they enter the multiplex printer mechanism. The device of this invention is not limited in its use to multiplex printer mechanism as it may be applied to any other equipment.

What is claimed is:

1. A device for shifting the distributor brushes of multiplex telegraph printers in equal amounts but opposite directions, in order to place a local and received signal in proper phase relation with respect to each other, comprising a frequency correcting unit for said received signal, a housing member, a rotatable shaft arranged to rotate simultaneously with a multiplex telegraph printer, two concentrically spaced gears each having teeth which face each other, said gears being arranged to rotate within said housing member, an operating shaft having bearings within said housing member, a pinion gear secured to said shaft and positioned to mesh with the teeth of each gear, insulating support means secured to each gear, a brush member secured to said insulating support means, a metallic collector ring, said ring being divided into two equal halves and insulatingly arranged on said rotatable shaft to rotate concentrically within said spaced gears to contact said brushes, and means to electrically connect said brushes through said collector ring with said frequency correction unit of a multiplex telegraph printer.

2. In a multiplex printer of the type having a distributor provided with two angularly disposed distributor brushes, means for shifting the relative positions of said brushes in equal but in opposite directions, said means including two parallelly spaced plates, a rotatable shaft arranged to extend within the space between said parallelly spaced plates and linked with the multiplex printer, an insulating disc secured for rotation with said shaft, a metallic collector ring located on the outer periphery of said insulating disc and engaging said distributor brushes, said ring being divided into two equal halves, an operating shaft, a pinion gear secured to an end of said operating shaft, inner and outer arcuate gears coaxially arranged to rotate between said parallelly spaced plates, insulating means to secure each of said brushes to said inner and outer arcuate gears, a gear support to space each gear in an operative position within said spaced plates, said pinion gear being positioned to mesh with the teeth of said spaced arcuate gears whereby motion which is applied to said operating shaft will move the gears of each pair in equal but in opposite directions to change the position of said brushes with respect to said pinion gear.

gears in equal but in opposite directions to change the position of said brushes with respect to said pinion gear.

3. In a multiplex printer of the type having a distributor provided with two angularly disposed distributor brushes, means for shifting the relative positions of said brushes in equal but in opposite directions, said means including two parallelly spaced plates, a rotatable shaft arranged to extend within the space between said parallelly spaced plates and linked with the multiplex printer, an insulating disc secured for rotation with said shaft, a metallic collector ring located on the outer periphery of said insulating disc and positioned to make electrical contact with said distributor brushes, said ring being divided into two equal halves, an operating shaft, a pinion gear secured to an end of said operating shaft, a plurality of inner and outer spaced arcuate gears coaxially arranged in pairs to rotate between said parallelly spaced plates, insulating means to secure each of said brushes to said inner and outer spaced arcuate gears of each pair, each gear support having a slot to permit the passage of a brush which is secured to an oppositely located arcuate gear, a gear support to space each gear of each pair in an operative position within said spaced plates, said pinion gear being positioned to mesh with the teeth of said spaced arcuate gears whereby motion is applied to said operating shaft will move the gears of each pair in equal but in opposite directions to change the position of said brushes with respect to said pinion gear.
4. In a multiplex printer of the type having a distributor provided with two angularly disposed distributor brushes, means for shifting the relative positions of said brushes in equal but in opposite directions, said means including two parallelly spaced plates, a plurality of spacing members for spacing said plates, means for binding said spacing members to said plates, a rotatable shaft arranged to extend within the space between said parallelly spaced plates and linked to rotate simultaneously with a multiplex printer, an insulating disc secured for rotation with said shaft, a metallic collector ring located on the outer periphery of said insulating disc and positioned to make contact with said distributor brushes, said ring being divided into two equal halves, an operating shaft, a pinion gear secured to an end of said operating shaft, a plurality of inner and outer spaced arcuate gears arranged coaxially in pairs to rotate between said parallelly spaced plates, insulating means to secure each of said brushes to said inner and outer arcuate gears of each pair, a gear support to space each gear of each pair in an operative position within said spaced plates, said pinion gear being positioned to mesh with the teeth of said spaced arcuate gears whereby motion which is applied to said operating shaft will move the gears of each pair in equal but in opposite directions to change the position of said brushes with respect to said pinion gear.
